UNITED STATES PATENT OFFICE.

ERYE L. ADAMS, OF MIDDLETON, IDAHO.

TRAIN-PIPE COUPLING.

992,627.

Specification of Letters Patent.

Patented May 16, 1911.

Application filed June 28, 1909. Serial No. 504,782.

To all whom it may concern:

Be it known that I, ERYE L. ADAMS, a citizen of the United States, residing at Middleton, in the county of Canyon, State of Idaho, have invented certain new and useful Improvements in Train-Pipe Couplings; and I do hereby declare the following to be a full, clear, and exact description of the invention, such as will enable others skilled in the art to which it appertains to make and use the same.

This invention relates to couplers of the kind designed to connect sections of car supported pressure pipe.

15 One object of the invention is to simplify the construction of devices of this character.

Another object of the invention is to provide a novel means whereby such devices will be caused to engage no matter whether 20 they are in exact alinement or not.

A third object of the invention is to provide a novel form of cut off valve for a device of this character when the same is not engaged with another section.

25 With the above and other objects in view the invention consists in general of a train supported pipe coupling of improved character in combination with a novel means for actuating a valve held in said coupler.

30 The invention further consists in certain novel details of construction and combinations of parts hereinafter fully described, illustrated in the accompanying drawings, and specifically set forth in the claims.

35 In the accompanying drawings, like characters of reference indicate like parts in the several views, and:—Figure 1 is a partial side elevation of two freight cars equipped with this invention showing the sections 40 thereof in coupling position. Fig. 2 is an enlarged detail view of one of the coupler heads. Fig. 3 is a detail perspective view of one of the suspending links. Fig. 4 is a detail perspective view of a portion of the 45 valve mechanism. Fig. 5 is a detail perspective view of the face of the coupler member.

50 The numerals 10 indicate railroad cars of any ordinary construction and beneath each of these cars are fixed eyes 11 wherein is 55 swingingly mounted a triangular plate 12 which extends transverse of the car and has

apertures 13 in the upper corners thereof to engage the eyes 11, and an aperture 14 in the lower corner thereof for purposes hereinafter to be described. Spaced from the eyes 11 and firmly secured to the car is a truss rod 15 which is bent downward and provided with an eye 16 at its lower median portion.

At 17 is indicated one of the pressure pipes of a train such as a steam or air pipe, and further this pressure pipe is connected in any suitable manner to a coupler end 18, which consists of a cylindrical portion adjacent the pipe 17 and an enlarged portion terminating in a relatively large face 19. Upon this enlarged portion is mounted an eye 20 which is engaged with the aperture 14 in the lower corner of the triangular plate 12. This coupling member is provided with a bore 21 of uniform diameter throughout its length and by means of this construction the walls of the coupling member adjacent the face 19 are much thicker than the coupling member adjacent the pipe 17. Attached to the eye 16 is one end of a spiral compression spring 22 which surrounds the cylindrical portion of the member 18 and has its opposite end bearing against a pin 23 projecting from the coupling member.

Upon the face of the member 18 is an elastic washer 24 provided with a plurality of countersunk openings 25 wherein are held screws 26 which serve to attach the washer 24 firmly to the face 19 while at the same time, the screw heads being below the face, do not interfere with the yielding of this washer under working conditions. It will be noted that the face 19 is at right angles 90 to the axis of the member 18 so that when two of these members come together the washers 24 abut.

Mounted beneath the car is a bracket 27 provided with a longitudinal slot 28. At 29 is indicated a butterfly valve the stems of which project laterally through the sides of the member 18 and which are squared at their free ends as indicated at 30. Mounted on each of these squared ends is a rock arm 100 31, the free ends of this rock arm being in spaced relation as can clearly be seen in Fig. 4. These rock arms lie one on each side of the bracket 27 and a bolt 32 passes

through openings 33 in the rock arms and through the slot 28.

In the operation of this device when two cars are brought together the washer 24 of one car will strike the washer 24 of the other car and this will cause each of the members 18 to be forced backward until the cars are coupled when they will be maintained in this position so long as the cars remain together. When in the forward position the valve 29 lies across the bore 21 but as the member 18 is pushed backward the ends of the rock arms 31 will be prevented from moving backward therewith and this will cause the valve 29 to rotate through a quarter of a circle and open communication between the portions of the member 18 lying on each side thereof. This backward motion is permitted by the yielding of the spring 22 and the swinging of the triangular supporting plate 12. As soon, however, as the cars are separated the spring 22 will again force the member 18 away from the center of the car and this will close the valve by the arm 31 moving through a quarter of a circle in the reverse direction to that just described.

There has thus been provided a simple and efficient device of the kind described and for the purpose specified.

Having thus described the invention, what is claimed as new, is:—

1. In a device of the kind described, a coupling member provided with a flat engaging face at right angles to the axis of the member, and means to yieldably support said member for longitudinal movement beneath a car, said means comprising a hanger swung from the bottom of a car and pivoted to said coupling member, a coil spring surrounding said member and having an upturned rear end provided with an eye adapted for attachment to a car, and a collar on said member resting against the forward end of the spring.

2. In a device of the kind described, a coupling member provided with a flat engaging face at right angles to the axis of the member, said face having an annular elastic washer secured thereto, and means to yieldably support said member for longitudinal movement beneath a car, said means comprising a hanger swung from the bottom of a car and pivoted to said coupling member, a coil spring surrounding said member and having an upturned rear end provided with an eye adapted for attachment to a car, and a collar on said member resting against the forward end of the spring.

3. In a device of the kind described, a hollow coupling member of uniform bore throughout and provided with an enlarged end having a flat engaging face at right angles to the axis of the member, and means to yieldably support said member for longi-

tudinal movement beneath a car, said means comprising a hanger swung from the bottom of a car and pivoted to said coupling member, a coil spring surrounding said member and having an upturned rear end provided with an eye adapted for attachment to a car, and a collar on said member resting against the forward end of the spring.

4. In a device of the kind described, a hollow coupling member of uniform bore throughout and provided with an enlarged end having a flat engaging face at right angles to the axis of the member, said face having an annular elastic washer secured thereto, and means to yieldably support said member for longitudinal movement beneath a car, said means comprising a hanger swung from the bottom of a car and pivoted to said coupling member, a coil spring surrounding said member and having an upturned rear end provided with an eye adapted for attachment to a car, and a collar on said member resting against the forward end of the spring.

5. In a device of the kind described, a coupling member provided with a flat engaging face at right angles to the axis of the member, means to yieldably support said member for longitudinal movement beneath a car, and a valve in said member actuated by the movement thereof, said means comprising a hanger swung from the bottom of a car and pivoted to said coupling member, a coil spring surrounding said member and having an upturned rear end provided with an eye adapted for attachment to a car, and a collar on said member resting against the forward end of the spring.

6. In a device of the kind described, a coupling member provided with a flat engaging face at right angles to the axis of the member, said face having an annular elastic washer secured thereto, means to yieldably support said member for longitudinal movement beneath a car, and a valve in said member actuated by the movement thereof, said means comprising a hanger swung from the bottom of a car and pivoted to said coupling member, a coil spring surrounding said member and having an upturned rear end provided with an eye adapted for attachment to a car, and a collar on said member resting against the forward end of the spring.

7. In a device of the kind described, a hollow coupling member of uniform bore throughout and provided with an enlarged end having a flat engaging face at right angles to the axis of the member, means to yieldably support said member for longitudinal movement beneath a car, a valve in said member provided with stems projecting laterally through the said member, rock arms fixedly connected to the stems, the free ends of said

arms being disposed in spaced relation, a bracket adapted to be connected fixedly to a car and arranged intermediate the free ends of the said arms, the said bracket being
5 provided with a longitudinal slot, and a pin arranged within the slot and connecting the ends of the rock arms.

In testimony whereof, I affix my signature, in presence of two witnesses.
